No. 36,823.

Patented February 23, 1904.

UNITED STATES PATENT OFFICE.

GEORGE W. LANKFORD, OF SPRINGFIELD, MISSOURI, AND WILLIAM H. KEITH, OF OTTAWA, KANSAS; SAID LANKFORD ASSIGNOR TO SAID KEITH.

DESIGN FOR A DOILY OR SIMILAR ARTICLE.

SPECIFICATION forming part of Design No. 36,823, dated February 23, 1904.

Application filed November 11, 1903. Serial No. 180,781. Term of patent 14 years.

To all whom it may concern:

Be it known that we, GEORGE W. LANKFORD, residing at and whose post-office address is Springfield, in the county of Greene and State 5 of Missouri, and WILLIAM H. KEITH, residing at and whose post-office address is Ottawa, in the county of Franklin and State of Kansas, citizens of the United States, have invented a certain new, original, and ornamental Design 10 for Doilies or Similar Articles, of which the following is a specification, reference being had to the accompanying drawing, forming a part hereof.

The figure is a plan view of a doily, showing 15 our new design.

What we claim is—

The ornamental design for a doily or similar article, as shown.

GEORGE W. LANKFORD.
WILLIAM H. KEITH.
